UNITED STATES PATENT OFFICE

158,174

MAKE-UP SHADE SELECTOR

Alfred Busiel, Glencoe, Ill., assignor to Lady Esther, Ltd., Chicago, Ill., a corporation of Illinois

Application July 20, 1949, Serial No. 4,027

Term of patent 14 years

(Cl. D86—10)

To all whom it may concern:

Be it known that I, Alfred Busiel, a citizen of the United States, residing at Glencoe, county of Cook, and State of Illinois, have invented a new, original, and ornamental Design for a Make-up Shade Selector, of which the following is a specification, reference being had to the accompanying drawing, forming a part thereof, in which:

Fig. 1 is a perspective view of a make-up shade selector, showing my new design; Fig. 2, a top plan view; Fig. 3, a bottom plan view; and Fig. 4, a side view in elevation.

I claim:

The ornamental design for a make-up shade selector, as shown.

ALFRED BUSIEL.
